UNITED STATES PATENT OFFICE

120,184

DESIGN FOR A WOVEN FABRIC

Henry Orville Hollingworth, Littleton, Mass.

Application February 5, 1940, Serial No. 90,037

Term of patent 7 years

To all whom it may concern:

Be it known that I, Henry Orville Hollingworth, a citizen of the United States, residing at Littleton, in the county of Middlesex and State of Massachusetts, have invented a new, original, and ornamental Design for Woven Fabrics, of which the following is a specification, reference being had to the accompanying drawing, forming a part thereof.

The single figure of the accompanying drawing is a plan view on an enlarged scale of a short section of a strip of fabric showing my new design.

I claim:

The ornamental design for a woven fabric, substantially as shown and described.

HENRY ORVILLE HOLLINGWORTH.
